[57] CLAIM

The ornamental design for an angled hosel adapted for a golf club, as shown and described.

DESCRIPTION

FIG. 1 is a top plan view of an angled hosel showing my new design;

FIG. 2 is a bottom plan view thereof;

FIG. 3 is a front elevational view thereof;

FIG. 4 is a rear elevational view thereof;

FIG. 5 is a side elevational view thereof; and,

FIG. 6 is an opposite side elevational view thereof.

The broken lines showing a golf club head and a golf club shaft in FIGS. 1-6 are for illustrative purposes only and form no part of the claimed design.
